UNITED STATES PATENT OFFICE.

HARRY J. McNABB, OF WEST CARROLLTON, AND RIAL T. PARRISH, OF DAYTON, OHIO.

DESIGN FOR A SPARK-PLUG.

57,080.

Specification for Design.

Patented Feb. 8, 1921.

Application filed May 1, 1920. Serial No. 378,300. Term of patent 7 years.

To all whom it may concern:

Be it known that we, HARRY J. McNABB, a citizen of the United States of America, and resident of West Carrollton, in the county of Montgomery and State of Ohio, and RIAL T. PARRISH, a citizen of the United States of America, and resident of Dayton, in the county of Montgomery and State of Ohio, have invented a new, original, and ornamental Design for Spark-Plugs, of which the following is a specification, reference

being had to the accompanying drawing, forming part thereof.

Figure 1 is an elevation of a spark plug member showing our design; and

Fig. 2 is a top plan view.

We claim:

The ornamental design for a spark plug, as shown.

HARRY J. McNABB.
RIAL T. PARRISH.
